Specification for Design.

Patented Nov. 22, 1921.

Application filed June 2, 1921. Serial No. 474,575. Term of patent 14 years.

To all whom it may concern:

Be it known that I, JEREMIAH McGREVY, a citizen of the United States, residing at Brooklyn, in the county of Kings and State of New York, have invented a new, original, and ornamental Design for a Ribbon Loop for Watchcases, of which the following is a specification, reference being had to the accompanying drawing, forming part hereof.

In the drawing,—

Figure 1 is a plan view of a ribbon loop showing my new design.

Fig. 2 is an end view thereof.

Fig. 3 is a lateral view thereof.

Fig. 4 is a lateral view looking from the opposite side than that from which Fig. 3 is viewed.

I claim:—

The ornamental design for a ribbon loop for watchcases, as shown.

JEREMIAH McGREVY.
